UNITED STATES PATENT OFFICE.

FOSTER J. DUNWOODY, OF DENVER, COLORADO.

PULVERIZED-SOAP CONTAINER AND DISPENSER.

970,479.

Specification of Letters Patent. Patented Sept. 20, 1910.

Application filed January 11, 1910. Serial No. 537,463.

To all whom it may concern:

Be it known that I, FOSTER J. DUNWOODY, a citizen of the United States of America, residing in the city and county of Denver 5 and State of Colorado, have invented a new and useful Pulverized-Soap Container and Dispenser, of which the following is a specification.

My invention relates to improvements in 10 pulverized soap containers and dispensers, and the objects of my invention are: First—to provide a powdered soap holding receptacle adapted for lavatories of hospitals, private residences, Pullman and other rail- 15 way cars, office buildings and hotels, that is provided with a manually operated powdered soap discharging valve mechanism that is adapted to agitate and prevent the clogging of the powdered soap, and provides 20 at the same time a positive force feed. Second—to provide a powdered soap holding and distributing receptacle that is so designed that splashed water or atmospheric moisture cannot come in contact with its 25 contents, and that can be secured to a suitable support against unintentional or accidental displacement; and third—to provide a simple, neat, inexpensive powder holding and distributing receptacle for powdered 30 soap, talcum, toilet and other powders.

I attain these objects by the mechanism illustrated in the accompanying drawings, in which:

Figure 1 illustrates a central, sectional view of my improved soap receptacle. Fig. 35 2 is a transverse, sectional view on line 2—2 of Fig. 1. Fig. 3 is a transverse, sectional view on the line 3—3 of Fig. 1. Fig. 4 is a side view illustrating a modification of the 40 valve operating lever; and Fig. 5 is a view of a key used in connection with the improved device.

Similar letters of reference refer to similar parts throughout the several views.

Referring to the drawings, the numeral 45 1 designates a cylinder or other tubular shaped cup, can, bottle or receptacle. I preferably use a round or tubular form of receptacle which may be made of any suitable material, but is preferably made of brass, nickel or aluminum tubing. This tube 50 is preferably open at its bottom portion and is provided with a hinged cap portion 2 which fits snugly to the top of the receptacle. This cap is preferably locked to the receptacle, and any suitable form of lock

may be used. I illustrate, however, a common form of padlock 3.

At a short distance from the bottom of the soap receptacle I place a partition or 60 floor portion 4, which is secured to it by any suitable means. This partition is preferably of a concave or dished form, as I find in practice that the concaved surface which forms the inside bottom of this soap 65 receptacle is especially adapted to permit the powdered soap to flow easily from the outer edges of this dish shaped partition to the discharge outlet. This discharge outlet 5 is positioned at the center of this dish shaped 70 partition which is at the lowest point of the cylinder. This outlet comprises a discharge port, the wall of which is tapered to register against the taper side of a taper plug shaped valve 7. This taper valve 7 is provided with 75 an axial threaded aperture which screws onto the threaded end of a valve stem 8. This valve stem extends below the lower end of the valve and a check nut 9 is threaded to the end of the valve stem against the 80 valve. The valve can thus be adjustably set on the valve stem. The lower end of the valve stem is pivotally secured below said valve and nut to one end of a lever 10 by a pin 11. The pin 11 extends through an 85 aperture formed through the end of the valve stem and extends into and through an oblong slot 14 formed through the end of the lever. The opposite end of this lever is pivotally secured by a pin 15 to a lug 16, 90 which is riveted or otherwise secured to the inside of the shell of the cylinder. Intermediate of the ends of this lever 10 I form a slot 17, to which is secured by a suitable pin or bolt 18 an arm 19, which depends 95 from a lever 20 which I term the valve operating lever. This lever is pivotally secured at one end to the opposite side of the inside wall of the shell of the cylinder from the lever 10, and it is formed centrally with 100 a semi-circular bend, as shown, which extends around the valve 7, and permits free downward movement of the same. The free end of the lever 20 extends through a slot 21 in the receptacle, and its outer end terminates in a finger pressing plate or button portion 22, adapted to receive the pressure of a finger of the hand of an operator. The arm portion 19 of this lever is positioned 105 between its finger portion and its semi-circular portion within the cylinder, and is arranged to push the lever 10 down when its 110

finger portion is pushed down, which movement causes the end of the lever 10 which is pivotally secured to the lower end of the valve stem to draw the valve stem and valve 5 down and open the soap outlet aperture 5, and thus allow the powdered soap to discharge from the receptacle.

The valve is held closed and the levers 10 and 20 are held up into their normal operative position by a conical coiled expansion spring 24, the base of which rests in the concave partition or dish, which forms an abutment for its lower end. The upper or apex end of this conical spring abuts 15 against a pin 25, which extends through the upper end of the valve stem. This valve and its stem and the conical spring occupy a vertical position in the receptacle and the valve stem and spring extend up into the 20 receptacle above the dish shaped floor a sufficient height to provide a spring of sufficient tension to hold the valve tightly closed and at the same time to permit the conical spring to act as an agitator of the powdered 25 soap during its compression movement when the valve is moved down to discharge the powdered soap, as the coils increase in diameter from the valve stem to the wall of the receptacle, thus agitating the whole body 30 of soap. When the spring is compressed once or twice or three times in succession the various coils move down through a different part of the area of the receptacle and consequently come in contact with the body 35 of powdered soap across its width and press it down toward the discharge outlet, which is open when the spring is pulled down by the valve stem, which assists in feeding the powdered soap through the valve and prevents 40 it packing or clogging throughout the area of the receptacle occupied by the spring, and when the finger plate is released the expansive force of the spring draws the stem and valve up and it moves up through 45 the soap powder, agitating, stirring and loosening it up, and thus keeping it in proper condition to discharge easily from the outlet opening. The conical spring alone is sufficient to prevent the clogging 50 and packing of soap and other powders, but in order to insure the positive feeding of the powder placed in the receptacle I provide the valve stem with a special form of powder agitator which exerts a positively 55 downward feeding movement on the soap or other powder, and while several forms of agitator could be attached to the valve stem or spring to accomplish this result, I preferably carry out my invention in the following manner: Upon the valve stem, a suitable distance above the upper end of the valve, is mounted in any suitable manner that will permit it to rotate thereon without vertical movement an agitator 26, 60 which comprises a central body portion 27,

from which extends a group of circumferentially arranged curved arms 28, which project downward and outward from the body portion. This agitator moves up and down with the valve stem in the powder and the arms are preferably given a spiral curve from the body portion to their terminal ends, which as the agitator is moved through the powder causes the said agitator to rotate upon the valve stem thereby loosening or agitating the powder so that it passes more easily through the discharge outlet.

The soap receptacle is provided with a projecting stem 29, which is secured to the opposite side of the receptacle from the valve operating finger plate. This stem has a reduced portion, which passes through a hole in the receptacle and is riveted or otherwise secured to a plate 30, which is secured to the interior of the receptacle. An aperture adapted to receive the stem of a screw 31 is formed transversely through the central portion of the stem. This stem is adapted to extend into the bore of a bracket 32, that is adapted to be secured to the wall of a room or splash plate of a wash-basin. The screw 31 is inserted through the sides of the bracket and extends loosely through the aperture in the stem, and is threaded in the opposite side of the bracket. The aperture in one side of the bracket is counter-bored to receive the head of the screw 31, which is provided with short screw driver receiving slots, which project into diametrically opposite side edges of the head of the screw 100 a short distance, thus leaving an unslotted portion on top of the head of the screw. These short slot portions in the head of the screw necessitate the use of a special form of key 32', which is illustrated in Fig. 5, and 105 enables the receptacle to be secured in operative position in a manner to prevent its being easily and quickly removed and stolen.

In Fig. 4 I illustrate a slightly different form of valve operating lever 33. The lever 110 is designed to receive removable push plates 34, having shanks 35, which are secured to the lever by a pin, thus providing for push plates of any desired design and provided with any desired word, name or symbol.

The valve opening finger pressing plates may be made in any design of form or shape or configuration desired, and any suitable words, such as "press" or "push down", or "soap" may be stamped or otherwise applied to it. Words or symbols may also be stamped or otherwise applied to the top of the cover, if desired.

My invention presents a thoroughly sanitary, valve controlled dispensing receptacle 125 for powdered soap, talcum, toilet and other powders.

Having described my invention, what I claim as new and desire to secure by Letters Patent is:

1. In a device as specified, a receptacle provided with a dished bottom near its lower end, having a discharge aperture; a conical valve in said aperture; a stem extending through said valve and into the receptacle; an abutment on said stem; a conical coil spring interposed between said abutment and the dished bottom; a lever connected with the lower end of said valve stem and extending through the receptacle and an agitator rotatably mounted on the valve stem, within the conical spring.

2. In a device as specified, the combination of a cylindrical casing, provided with a cap and with a concave bottom adjacent to its lower end having a discharge outlet therein; a valve in said outlet; an adjustable stem extending through said valve; an arm pivotally attached at one end to the lower ends of the stem and at its opposite end to the casing; an operating lever pivotally attached to said arm and to the casing, the free end of which projects out through a slot in the casing; a spring for normally seating the valve; and a rotatable agitator on the valve stem.

3. In a device as specified, a receptacle; a concave bottom in said receptacle, adjacent to its lower end, having a central opening; a plug valve in said opening; a stem extending beyond each end of said valve, having a

pin extending through its upper end; a spring under tension between said bottom and said pin; an arm pivotally attached to the lower end of said stem and to the receptacle; and a lever pivotally attached at one end to the receptacle, and extended through a slot in the opposite side of the same, and having a depending member which is pivotally connected to said arm.

4. In a device as specified, a receptacle provided intermediate of its ends with a concave bottom having an outlet aperture; a plug valve in said aperture; a threaded stem in said valve and a check nut on said stem; an arm pivotally attached at one end to the lower end of the stem and at its opposite end to the casing; a lever pivoted at one end to the casing and having a depending member which is pivotally attached to said arm, and a semi-circular bend concentric with and adapted to extend around said plug valve, the opposite end of said lever projecting through a slot in the receptacle; a spring for normally seating the valve; and an agitator on the valve stem.

In testimony whereof I affix my signature in presence of two witnesses.

FOSTER J. DUNWOODY.
